LENS MARKER

Jack L. Brenner, Utica, N. Y., assignor to Shuron Optical Company, Inc., Geneva, N. Y., a corporation of New York

Application August 12, 1937, Serial No. 158,779

5 Claims. (Cl. 101—41)

This invention relates to improvements in a device for stamping or marking either a flat, concave or convex surface of a lens or analogous object.

In the usual method of marking a lens, three dots are printed in line across a surface of the lens substantially coincident with the optical axis of the lens. These dots are formed by means of a corresponding number of resiliently mounted pins operated by a suitable lever mechanism in conjunction with a lens holding device or chuck and an ink well or pad. These dots serve as reference points in the laying out and gauging of the lens. When the lens is to be drilled or cut for edging, it is desirable to draw a straight line across the surface of the lens extending through the dots. This latter operation has heretofore been accomplished by placing a ruler or straight edge across the lens in alignment with the three dots and then drawing the line with a pen. This manner of marking is very unsatisfactory owing to the difficulty of drawing a line accurately over the curved surface of the lens and of making a full, clear, clean-cut line with pen and ink on glass.

The main object of this invention is to produce an instrument which is simple in construction and operation, whereby a line or other indicia may be quickly and easily printed on the smooth surface of a lens or other similar object.

Another object is to provide an instrument of the above mentioned class which will apply a line or other indicia to the lens surface with equal efficiency whether the surface is flat, concave or convex in outline or general configuration.

Other objects and advantages pertaining to the specific construction of the machine will more clearly appear from the following description taken in conjunction with the accompanying drawings in which:

Figure 1 is a top plan of a machine embodying the various features of this invention.

Figure 2 is a side elevation of the machine illustrated in Figure 1.

Figure 3 is a detail horizontal sectional view on an enlarged scale, taken in the plan of the line 3—3, Figure 2.

Figures 4 and 5 are detail sectional views taken respectively on lines 4—4 and 5—5, Figure 3.

Figures 6 and 7 are detail horizontal sectional views illustrating my novel printing device in operative engagement with a concave surface and a convex surface respectively of a lens.

Figure 8 is a top plan of a machine illustrating a modified form of my device.

Figure 9 is a side elevation of the structure shown in Figure 8.

Figure 10 is a vertical sectional view taken substantially on line 10—10, Figure 9.

Figure 11 is a detail vertical sectional view taken on line 11—11, Figure 8.

The structure shown in Figures 1 to 5 inclusive of the drawings comprises a base 1 having a vertically disposed standard 2 extending upwardly from one end thereof, and a substantially horizontally disposed bracket 3 projected from the opposite end for supporting a box 4 adapted to contain an ink pad 5, as indicated in Figure 2. The box 4 is provided with a lid or cover 6 hingedly connected, as at 7, to one side of the box.

The standard 2 has secured thereto a lens holder or chuck 9, which may be of any suitable construction, for supporting a lens, as L, in a vertical plane above the base 1. The chuck 9, as shown, comprises a vertically disposed frame 10 connected at its lower end to the standard 2 as by bolts 11. The upper end of the frame 10 is provided with an aperture 10' extending therethrough and a plurality of horizontally disposed resilient posts 12 of soft rubber or equivalent material, having their outer ends projecting a uniform distance from the inner surface of the frame 10 for receiving and supporting the lens L at one side of the frame in alignment with the aperture 10'. A clamp 13 is hingedly connected, as at 14, to the frame 10 at one side of the posts 12. This clamp extends outwardly from the pivot 14 a relatively short distance to provide a finger piece 15 arranged in cooperative spaced relation to a similar finger piece 16 made integral with the frame 10. The clamp 13 also extends inwardly from the pivot 14 and is provided with a pair of spaced resilient fingers 17 adapted to engage the lens L at opposite sides of the horizontal center thereof. The clamp fingers 17 are yieldingly urged toward the posts 12 for maintaining the fingers in engagement with the lens L by a spring 18 coiled around the pivot pin 14 with the ends thereof engaging the finger pieces 15 and 16, as illustrated in Figure 3.

The marking device comprising the novel feature of this invention includes a carrier frame 20 pivoted at one end to the base 1 by a pin or shaft 21 mounted in an upwardly extending boss 22 connected with the base 1 a short distance inside of the standard 2, so that the frame 20 may swing about a horizontal axis at right angles

to the longitudinal center of the base 1 and chuck 9. The upper end of the frame 20 is provided with a bifurcated head 23 arranged at one side of the frame and in which is journaled a shaft or spindle 24 connected to a drum or holder 25. The drum or holder 25 is provided with a slot 25' extending longitudinally therethrough. A pair of movable supports or arms 26 are pivotally connected at one end by pins 27 in the slot 25' in longitudinal spaced relation to each other and at equal distance either side of the vertical plane passing through the chuck 9 centrally of posts 12 and aperture 10'. These supports or arms extend outwardly from the slot 25' toward the lens chuck 9 and have the outer ends thereof pivotally connected by pins 28 to space lugs or ears 29 secured to respective ends of a flexible platen 30 composed of spring steel, brass or the like.

The platen 30 is normally curved from the arms 26 toward the chuck 9, as illustrated in Figures 1 and 3 and has secured to substantially the center thereof, one end of a pin 31 which extends rearwardly from the platen into a diametrically disposed aperture 32, formed in the drum 25 to extend through the slot 25' substantially midway between pins 27. The pin 31 may be secured to the platen 30 by any suitable means, and for this purpose the forward end of the pin is reduced in diameter to extend through a corresponding hole 30' provided in the platen and has the forward end thereof upset, as illustrated in Figure 4. The pin 31 is slidably received in the aperture 32 for maintaining the platen 30 in symmetrical relation with the pivots 27 and at the same time permit ready flexing of the spring from an outward convex position, as illustrated in Figures 1, 3 and 6, to an inward concave position as illustrated in Figure 7.

The outer or forward convex side of the platen 30 has secured thereto a die member 33 composed preferably of rubber or other flexible or elastic material. This die member 33 may be secured to the platen 30 by any suitable means, as glue, cement or the like. The die 33 has the indicia, which in this instance is in the form of a raised ridge 34 moulded thereto to provide a gauge line extending longitudinally of the die 33 and platen 30. In addition to the longitudinally extending ridge 34, the die is provided with a centrally disposed, transversely extending ridge 35 bisecting ridge 34. The die may, as shown, be provided with two additional transversely disposed ridges 35' arranged at opposite sides of the centrally disposed ridge 35. The end ridges 35' are spaced from the central ridge 35 a distance substantially equal to the distance the end marking pins of a conventionally constructed lens marking device are from the centrally disposed marking pins. It will thus be seen that when the die 33 is brought into engagement with the surface of a lens or the like, a straight line will not only be stamped upon said surface but the die will also stamp relatively short lines across the main line at the center of the lens and at opposite sides of said center. Instead of a line or lines, it will be obvious that letters, figures or other indicia may be formed on the outer surface of the die 33.

The relation of the shaft 21 to the ink box 4, chuck 9 and spindle 24 is such that when the frame 20 is swung about the shaft 21 as a pivot, the drum 25 will be moved from a position in front of the chuck 9 to a position over the box 4, and in order to automatically position the die 33

in cooperative relation with the chuck and box at these positions of the frame, I have secured to the spindle 24 a gear member 37 which is mounted upon the spindle between the head members 23, as illustrated in Figures 1 and 3. The gear member 37 is secured to the spindle 24 by a pin 42 so as to rotate with said spindle and to also cooperate with the inner positioned head member 23 for maintaining the drum 25 against axial displacement.

In meshing engagement with the gear member 37 is a toothed rack 38 which is slidably received within a tubular arm 39 pivotally secured to the base 1 by a pin 40 connected with said base intermediate the shaft 21 and bracket 3. A spring 41 mounted within the arm 39 has one end connected with the pin 40 and the other end thereof connected to the rack member 38. The spring 41 is normally tensioned so as to hold the frame 20 and the marker platen 30 in an intermediate position below the plane of a lens mounted in the chuck 9. The toothed rack 38 is held in operative engagement with the gear member 37 by means of a back rest 44, as shown in Figures 1 and 2.

It will now be evident that when the frame 20 is rocked toward the box 4, the spring 41 will be under compression, and when moved to its marking position said spring will be under tension, thereby producing full rocking movement of the platen 30 from one extreme position to another as limited by the engagement of the pin 42, which is extended outwardly at opposite sides of gear 37, with a stop pin 43 secured to the frame 20.

The frame 20 is rocked about the shaft 21, in this instance by means of a rock arm 45 secured to a shaft 46 journaled in a boss 47 connected with the base 1 intermediate the pin 40 and bracket 3. The arm 45 has a finger piece 47 connected with the outer or free end thereof whereby the arm may be manually moved about the axis of the shaft 46. The arm 45 is connected with the frame 20 by a link 48 which is pivotally connected at its ends with said frame and arm.

In order that the cover 6 for the box 4 may be automatically moved to the open position during the movement of the frame 20 and platen 30 toward the box 4, I have provided a link 50 pivotally connected at one end, as at 51, to one side of the cover. The link 50 is provided with an elongated slot 50' in the opposite end thereof which slidably receives therein a screw 52 screw-threaded in an arm 53 connected with the end of the shaft 46 opposite the arm 45.

The operation of my novel lens marking device will now be understood to be substantially as follows:

As hereinbefore stated, the platen 30 is normally curved outwardly from the end pivots 28 toward the chuck 9 and the curve of the platen when in its end position will be of a shorter radius than the curve of any lens or other surface that may be marked, so that the central portion of the platen 30 or die 33 will come into contact with the surface to be marked first and then the adjacent side portions of the die will be progressively moved into contact with the surface as the platen continues to move toward the work. This is true whether the surface is concave, flat or convex in outline. In other words, after the lens L has been properly positioned in the chuck 9 in any suitable manner not herein necessary to illustrate or describe, the frame 20 may be first moved from the normal intermediate position 75

thereof as determined by the action of the spring 41, downwardly toward the box 4. As the head 23 of the frame and the platen 30 carried thereby approaches the box 4, the link 50 will be actuated by the arm 53 to open the cover or lid 6. 5 At the same time, the drum or holder 25 will be rotated in the head 23 by the action of the rack 38 upon the gear 37 to bring the platen 30 into such position, that the die 33 may engage the ink pad 5 contained in the box 4. Inasmuch as the 10 surface of the die 33 is of convex form, it will be evident that the central portion of the die will engage the pad first and remaining side portions of the die may be readily brought into contact 15 with the pad by a continued rocking of the arm 45 toward box 4 to produce a slight pressure upon the frame 20. During this additional swinging movement of the frame toward the box 4, there will be no relative swinging movement of the platen 30 with respect to the frame 20, due to 20 the engagement of one of the stop arms 42 with the stop pin 43. After the die 33 has thus been inked, the frame 20 is swung upwardly about the shaft 24 as an axis to the vertical position thereof. 25 During this upward swinging movement, the cover 6 will return to its normal closed position so as to maintain the box 4 normally closed to prevent evaporation or drying of the ink in the pad 5. Furthermore, the platen 30 will be rotated in an anti-clockwise direction by the rack 38 and gear 37 until the other stop arm 42 is brought into engagement with the pin 43, whereupon said platen will be maintained in substantially right angular relation with the upper portion 30 of the frame 20, or in substantially a horizontal plane when said frame is in the vertical position.

Assuming now that the surface of the lens, or other object supported in the chuck 9 to be engaged by the die 33, is of convex form as illustrated in Figure 6, the central portion of the die will first engage the central portion of the lens, and as the frame 20 and platen 30 continue to move in a direction toward the lens, the end portions of the platen will be flexed outwardly or 40 forwardly to bring corresponding portions of the die into engagement with the adjacent portions of the lens surface. This flexing of the platen will be readily accomplished due to the pivotal connection of the arms 26 with said platen and the drum or holder 25, and the degree of flexing 45 of the arm will be relatively slight, depending upon the amount of curvature of the concave surface engaged by the die. If however, the 50 surface to be engaged is of convex form as illustrated in Figure 7, the flexing of the platen and die will be considerably more than when marking a concave surface. However, the platen will be 55 readily flexed in marking the convex surface by engagement, first, of the central portion of the die with the central portion of the surface, and then the movement of the arms 26 readily permit flexing of the platen until the surface thereof to 60 which the die 33 is connected assumes a concave form corresponding to the curvature of the convex surface being marked. During this flexing of the platen and die, these members will be 65 maintained in substantially symmetrical relation with the pivots 27 and with the surface of the work to be marked by the co-action of the pin 31 and drum 25.

The structure shown in Figures 1 to 5 inclusive is adapted more particularly to be used in place of the conventional lens marking device 70 having three or more yieldingly supported mark-

ing pins. In using the structure of the instant application, the lens surface will obviously not only be provided with a line extending across the surface thereof from substantially one edge to the other in predetermined relation with the optical axis of the lens, but the cross ridges 35 and 35' will cooperate with the straight line ridge 34 in indicating the position of the center of the lens and predetermined spaced portions thereof.

In the device shown in Figures 8 to 11 inclusive of the drawings, I have illustrated a structure adapted more particularly for marking the axial line of the lens after the optical center and/or axis thereof has been determined. In other words, as hereinbefore stated, after a lens has been marked with a center dot and two outside dots by means of a conventional lens marker, or in any other suitable manner, the device shown in these figures is then used for producing a line across the lens in predetermined relation with the dots. This structure comprises a base 55 having a frame 56 of substantially H formation pivotally connected to the central portion thereof by a shaft 57, fixedly mounted in a pair of upwardly projecting bosses 58 connected to said base 55. The upper or outer end portions of the frame rotatively receive therein a shaft 59 to which is secured in any suitable manner the drum or holder 25.

This drum or holder 25 carries the platen 30 which is connected thereto by the arms 26 and pin 31 in the manner hereinbefore described for the structure shown in Figures 1 to 5 inclusive. One end of the shaft 59 extends outwardly beyond the adjacent side of the frame 56 and has fixedly secured thereto a pulley 60 which is arranged in alignment with a similar pulley 61 secured to one end of the shaft 57, which also projects beyond the corresponding side of the frame 56. Trained about the pulleys 60 and 61 is a belt 62 which is secured to said pulleys by pins 63. The frame 56 is provided with a handle 64 by which said frame may be swung about the shaft 57 as an axis. During this swinging movement of the frame, the drum or holder 25 will be rotated a corresponding degree owing to the pulley 61 being maintained in a fixed position with respect to the shaft 57 and base 55, while the pulley 60 will be rotated by the belt and thereby produce a corresponding rotation of the shaft 59 and holder 25.

A box 4 is secured to the base 55 adjacent one end thereof for containing the ink pad 5. A lens support 66 is mounted at adjacent the opposite end of the base for supporting the lens in cooperative relation with the platen 30 when the frame is moved downwardly toward said end portion of the base.

This lens support, as shown more clearly in Figure 11, comprises a case 67 which is rotatably connected with the base 55 by a centrally disposed pin or stud 68 connected with the case 67. A washer 69 may, as indicated in Figure 11, be mounted upon the stud 68 intermediate the case 67 for maintaining said case in slidably spaced relation to the upper surface of the base 55. Mounted in the case 67 is a pad 70, composed of rubber or other resilient materials, adapted to be engaged by the lens for frictionally maintaining said lens in co-axial relation with the stud 68.

Associated with the lens support 66 is a protractor 72, which in this instance is in the form of a substantially semi-circular ring, composed of any suitable material and secured to the base 55 in concentric relation with the holder 66. The 75

ring 72 is provided with a protractor scale 73 in the upper surface thereof which has its axes or center, coincident with the axis of the lens support 66 and is graduated from "0" to "180" from a horizontal line passing through its center in parallel relation with the shaft 57 to enable the operator to read the angle or degree of inclination of the optical axis of a lens from its horizontal or geometrical axis.

10 In using the device shown in Figures 8 to 11 inclusive, the cover 6 for the box 4 is manually moved to an open position when it is desired to apply the ink to the die 33, and the platen 38 and die 33 are swung about the axis of the shaft 57 into engagement with the ink pad 5 contained in the box 4 and then into engagement with the lens L carried on the lens holder 66. Prior to inking the die 33, a lens which has previously been marked with three or more dots on the surface thereof to define the optical axis or some axis at a predetermined angle to the optical axis of the lens is placed upon the lens holder 66, with the dots coinciding with the axis marker or line X provided on the pad 10.

20 25 It will now be observed that if the horizontal axis, that is, the axis of the lens appearing before the eye when the lens is positioned in a suitable ophthalmic mounting which is to be marked on the lens by the die 33 is to be different from the optical axis, the lens may be rotated by rotation of the case 67 so as to bring the line X, and therefore the optical axis of the lens, into predetermined angular relation with the die 33 as determined by the protractor 72 so that the line 30 stamped on the lens by the die will be at a given angle to the optical axis of the lens.

35 During the engagement of the die 33 with the lens, it will be understood that the platen 38 will be flexed in the manner hereinbefore described in the structure shown in Figure 1 to 5 inclusive, after the central portion of the die 33 has engaged the central portion of the lens to progressively move the outer side portions of the die into engagement with the lens surface. Furthermore, it will be understood that the frame 56 may be yieldingly maintained in its uppermost vertical position by any suitable means, as a spring 75, coiled upon the shaft 57 with one end thereof in engagement with the boss 58 and the other end in engagement with the frame 56.

40 45 Although the construction and operation of the devices shown are particularly simple, practical and efficient, it is evident that various changes may be made in the details of the construction thereof without departing from the spirit of the invention as set forth in the appended claims.

I claim:

1. In a precision marking device of the class described, a platen composed of a relatively thin substantially flat piece of resilient material capable of being flexed transversely of the opposed surfaces thereof only, said platen being normally curved in one direction of said flexing movement thereof to provide the platen with a normally convex work surface, indicia provided on said working surface, and supporting means for the platen including a carrying member and holding elements operatively engaging spaced portions of said member and the platen adapted to maintain said platen in an extended position with respect to said carrying member so that said platen is free to be flexed by pressure engagement thereof with the work to be marked to bring said work surface from the normal convex position thereof at one side of a flat medial plane to a concave po-

sition at the opposite side of said plane whereby the indicia may be brought into cooperative engagement with either a concave, a substantially flat or a convex work surface for marking the same by relative movement of the platen and work into pressure engagement with each other.

2. In a precision marking device of the class described, a platen composed of a relatively thin substantially flat piece of resilient material capable of being flexed transversely of the opposed surfaces thereof only, said material being inherently curved in one direction of said flexing movement independently of any external force to provide the platen with a normally convex working surface, indicia provided on said working surface, and supporting means for the platen including a carrying member, and holding elements operatively engaging spaced portions of said member and the platen adapted to maintain said platen in an extended position with respect to said carrying member, said holding elements having movement with respect to each other and being of such a character that said platen will freely flex as it is brought into engagement with the work to be marked so that said working surface may be moved from the normal convex position thereof at one side of a flat medial plane to a concave position at the opposite side of said plane to bring the indicia into cooperative engagement with either a concave, a substantially flat or a convex work surface for marking the same by relative movement of the platen and work alone into pressure engagement with each other.

3. In a precision marking device of the class described, a platen composed of a relatively thin substantially flat metallic spring member capable of being flexed transversely of the opposed surfaces thereof only, said platen being normally curved in one direction of said flexing movement thereof to provide the platen with a normally convex work surface, indicia provided on said convex work surface, and supporting means for the platen including a carrier, and holding elements pivotally connected to the platen and to said carrier to swing about relatively fixed axes on said carrier, said holding elements being adapted to maintain said platen in an extended position with respect to the carrier so that said platen is free to be flexed by pressure engagement thereof with the work to be marked to bring the work surface from the normal convex position thereof at one side of a flat medial plane to a concave position at the opposite side of said plane; whereby the indicia may be brought into cooperative engagement with either a concave, a substantially flat or a convex work surface for marking the same, and a separate member secured to the platen and slidably supported by the carrier for maintaining the platen in symmetrical relation with said fixed axes during the flexing of said platen.

4. In a lens marking device, a lens holder, a platen comprising a thin, flat elongated spring, said spring being normally curved longitudinally in one direction to provide the same with a convex work surface, indicia provided on said convex work surface for marking a lens on the lens holder, supporting means for the platen including a carrier member arranged at the concave side of the platen in spaced relation thereto, holding elements spaced from each other longitudinally of the platen connecting said platen to said carrier, said holding elements being so constructed and arranged that the carrier will be spaced from the lens holder and lens when said lens is engaged by the indicia on the platen, and

means for producing relative movement of the carrier and the lens holder to bring the lens and platen into and out of cooperative engagement with each other.

5. In a lens marking device, a supporting member, a platen comprising a substantially flat normally arcuate spring member, means including a pair of arms pivotally connected with the ends of the spring member and with the supporting member for connecting said spring member to the supporting member in spaced relation thereto so that the spring may freely flex toward and

from the supporting member from one side of a flat medial plane to the opposite side thereof, a guide member connected with the spring and supporting member for maintaining said spring against transverse and excessive longitudinal movements during the flexing thereof, and indicia connected to the outer surface of the spring adapted to be progressively moved during said flexing of the spring into marking engagement with a surface of a lens. 5

10 JACK L. BRENNER. 10
